UNITED STATES PATENT OFFICE.

CHARLES H. GREBENSTEIN, OF NEW YORK, N. Y.

MACHINE FOR CASTING CANDIES.

SPECIFICATION forming part of Letters Patent No. 364,342, dated June 7, 1887.

Application filed December 27, 1886. Serial No. 222,583. (No model.)

To all whom it may concern:

Be it known that I, CHARLES H. GREBENSTEIN, of the city, county, and State of New York, have invented certain new and useful 5 Improvements in Machines for Casting Candies, of which the following is a specification.

This invention relates to an improved machine for casting or dropping candies, such as gum-drops, cream-candies, and other round or 10 ornamental confectionery which are run into starch or india-rubber molds; and the invention consists of a machine for casting or dropping candy composed of a jacketed receptacle having an inclined bottom, a transverse opening 15 at the lower front part of the receptacle, a detachable gage having discharge-holes and noses formed below said holes, a vertically-reciprocating knife guided in front of said gage and operated by a pivoted lever-frame for opening 20 or closing the discharge-holes of the gage, and a stop device operated by said lever-frame for imparting to the receptacle a step-by-step motion over the mold, as will be fully described hereinafter, and finally be pointed out in the 25 claims.

In the accompanying drawings, Figure 1 represents a vertical longitudinal section on line *y y*, Fig. 2, of my improved machine for casting or dropping candies. Fig. 2 is a front elevation of the same, showing the mold in section. Fig. 3 is a plan view, partly in horizontal section on line *x x*, Fig. 1; and Fig. 4 is a side view of the machine, showing the device for intermittently moving the machine 30 forward or backward over the mold.

Similar letters of reference indicate corresponding parts.

Referring to the drawings, A represents a receptacle for the paste of which the candy or 40 other confectionery is made. The receptacle A is made of double walls, so as to form a jacket, A', for steam or hot water, by which the paste at the interior of the receptacle is kept in a proper degree of liquidity. The bottom of the receptacle A is made slanting toward the front wall, which latter is provided with a transverse opening, *a*, at the lower end of the bottom. The opening *a* communicates with an interchangeable gage, B, having drop-holes *b*, one gage having a smaller number of larger holes and another gage a larger number of smaller holes, so that candies of dif-

ferent sizes can be cast or dropped by the machine. The jacket A', formed by the double walls of the receptacle, is connected with 55 suitable steam or hot-water pipes, (not shown in the drawings,) and the receptacle closed at the top by a detachable cover, A².

A gate, C, is arranged at the interior of the receptacle A, and extended transversely across 60 the discharge-opening *a*, made of sufficient height to close said discharge-opening when pushed down on the bottom of the receptacle A. The gate C is provided with a handle, C', that extends through a recess of the cover A², so 65 that the gate can be raised or lowered from the outside of the receptacle.

The gate C can be guided in any suitable manner on the receptacle, and serves for shutting off the discharge-opening *a* whenever it is 70 desired to change the gage from one size to another. The discharge-holes *b* of the gage B are preferably made slanting, so that the pasty mass in the receptacle can readily flow through the same to the outside of the gage, being 75 dropped along noses *d*, formed by the recesses or notches *d'*, which are arranged immediately between the holes, as shown clearly in Fig. 2. The noses *d* prevent the running together of the drops and facilitate the dropping 80 of the same into the starch or rubber mold D, that is located below the machine on the table on which the machine is supported.

The receptacle A is placed on wheels, which are guided on rails of the table and intermittently moved backward or forward over the mold D, so as to successively fill the depressions of the same with candies. It is obvious that, instead of making the receptacle movable and the mold stationary, the receptacle may be 85 made stationary and the mold movable.

At the front wall of the receptacle A, and close to the gage B, is guided in suitable ways, *e*, a reciprocating knife, E, which is hinged by straps *e'* to a transverse bar or stay, E', of a 90 lever-frame, E², which is pivoted to the side walls of the receptacle, as shown in Figs. 1 and 2. The lever-frame E² is moved downward by the attendant, so that the knife E is lowered when the required quantity of paste has been 95 delivered through the holes, so as to cut off the drops, or raised so that the knife E clears the discharge-holes *b* and permits them to deliver another set of drops to the mold. After 100

one set of drops have been cut off and delivered to the mold, the receptacle is moved backward over the next row of depressions of the mold, the motion being interrupted by an 5 intermittently-actuated stop device, F, which consists of two notched wheels, f, that are pivoted to the lower parts of the side walls of the receptacle and engaged by fulcrumed pawls f', the upper ends of which are engaged by 10 the pivoted side arms of the lever-frame E², so that the lower ends of the pawl are released from the notches of the wheels f whenever the lever-frame E² and knife E are lowered, as shown in dotted lines in Fig. 4.

15 As soon as the pawls f' are withdrawn from the notches of the wheels f, the receptacle A can be moved backward over the mold for the distance of one tooth of the stop-wheels. By the raising of the frame and knife the pawls f' 20 are released and dropped by gravity into the next notch of the stop-wheels, so as to interrupt the backward motion and stop the receptacle, which is then held in position by its own weight and the friction of the stop-wheels with the 25 supporting-table until the pawls are released again. In this manner a step-by-step motion that corresponds to the distance between the centers of the rows of depressions of the molds is imparted to the receptacle. For different 30 sizes of gages and depressions in the molds differently notched stop-wheels are used.

It is obvious that in place of stop-wheels any other equivalent stop device may be used, such as a rack-bar fixed to the table and intermittently-locking drop-pins or any other suit- 35

able device, as I do not confine myself to the special stop mechanism shown.

Having thus described my invention, I claim as new and desire to secure by Letters Patent—

1. A machine for casting or dropping can- 40 dies, constructed with a jacketed receptacle having a transverse front opening, an interchangeble gage provided with discharge-holes in front of said openings and drop-noses below said holes, and with a vertically-recipro- 45 cating knife for cutting off the drops, substan- tially as set forth.

2. In a machine for casting or dropping can- 50 dies, constructed with a jacketed receptacle having a slanting bottom and a transverse front opening, an interchangeble gage having discharge-holes and drop-noses below said holes, a vertically-reciprocating knife in front of said gage, and a lever-frame for operating said knife, substantially as set forth.

3. The combination, with a paste-receptacle mounted on wheels and having a transverse discharge-opening, of a gage having discharge-holes and a vertically-guided knife, a lever- 60 frame for operating said knife, and an inter- mittently-actuated device operated by said lever-frame, substantially as set forth.

In testimony that I claim the foregoing as my invention I have signed my name in presence of two subscribing witnesses.

CHARLES H. GREBENSTEIN.
